UNITED STATES PATENT OFFICE.

JOHN B. ZORN, OF KANSAS CITY, MISSOURI.

DUSTER AND WASH STICK.

Application filed October 10, 1927. Serial No. 225,341.

The object of my invention is to provide a novel duster and wash stick which will permit of conveniently and quickly attaching and detaching the duster mop or sponge; 5 and to provide novel means for attaching an extension handle to a device of this character.

In attain these and other objects of my invention by the mechanism illustrated in 10 the accompanying drawings, in which,—

Figure 1 is a perspective view of my invention with the mop or duster rag attached;

Fig. 2 is a plan view of the device with the 15 duster or mop removed;

Fig. 3 is a longitudinal section on line 3—3 of Fig. 2, but with member 7 in position to detach the mop;

Fig. 4 is a detail sectional view on line 20 4—4 of Fig. 3;

Fig. 5 is a detail plan view of the mop engaging portion of the device, partly in section;

Fig. 6 is a plan view of the extension 25 handle attachment; and

Fig. 7 is a longitudinal section on line 7—7 of Fig. 6.

Like numerals designate like parts in each of the several views.

Referring to the accompanying drawings 30 I provide a handle 1 of suitable light material such as an aluminum alloy and having a longitudinal slot 2 extending from the end through the major portion of the handle.

A pivoted mop retaining rod or bar 7 is 35 mounted in the slotted portion of the handle by means of the pin 8, said bar having a rounded end 7' adapted to engage the head 4 of the spring-controlled locking pin or bolt 5. The head of bolt 5 is normally

pressed into locking position over the top edge of the end of member 7 by a suitable spring 6 which is seated in the recess 3' and presses against pin 5. The pin 5, which 40 preferably is square in cross section as shown in Fig. 4, is slidable in the slotted portion 3.

Attached to the end of handle 1 is a mop 45 engaging metal loop 9 having its ends 10 embedded in the end of handle 1 as shown in Fig. 2. The metal loop 9 may, if desired, be covered by suitable rubber tubing 13, as shown in Fig. 5.

Referring to Figs. 2, 6 and 7, I prefer to 50 provide a depression 11 near the end of handle 1 to receive the indentation 19 of the

resilient strip 17 of the metal sleeve 15 carried by the extension handle 14, as shown in Figs. 6 and 7. I provide suitable pins 16 to securely fasten the sleeve 15 to the 60 extension handle 14.

In operation the pin or bolt 4 is pressed backward so as to disengage it from the adjacent end of the bar 7, permitting the latter to tilt as shown in Fig. 3. A suitable 65 duster, rag, mop or sponge may then be placed over it and it be returned to its normal position parallel with the handle 1 and seated in the slot 2 thereof, as shown in Figs. 1 and 2, thus holding the mop 12 in engagement with the metal loop 9 as illustrated.

For the purpose of using the device for window washing or elsewhere where a long handle is desired, I may readily attach an extension handle by the means illustrated in 70 Figs. 6 and 7, the member 7 releasably engaging the end of the handle so that it may be readily snapped into and releasably locked in engagement with the handle of the wash stick.

The device may be used advantageously 75 for washing dishes or pans and also as a bath brush or shoe brush, or it may be used to hold a chamois or a squeegee to wash and dry windows.

What I claim is—

1. In a device of the class described, the combination of a handle having a longitudinal slot therein, a bar pivotally mounted in and extending parallel with the handle, a 90 fastening device contained within the handle and releasably holding the bar in locked position within the handle, and a metal loop mounted in the end of the handle and extending in spaced relation to and around the 95 free exposed end of the aforesaid bar.

2. In a device of the class described, the combination of a handle having a longitudinal extending slot therein, a bar pivotally mounted near the end of the handle and 100 adapted to be swung to substantially concealed position in the aforesaid slot and having an exposed portion extending beyond and parallel with the handle, a mop retaining loop member affixed to the aforesaid end of the handle and extending in spaced relation to and around the exposed portion of the aforesaid bar, a locking pin contained within the handle and having its head normally engaging over the end of the 110 aforesaid bar, a spring mounted in the handle and engaging said pin to normally

press it into locking engagement over the end of the bar.

3. In a device of the class described, the combination of a handle having a longitudinal extending slot therein, a bar pivotally mounted near the end of the handle and adapted to be swung to a substantially concealed position in the aforesaid slot and having an exposed portion extending beyond and parallel with the handle, a releasable locking pin, the bar having its other end curved to provide a sliding contact with the

releasable locking pin, a mop retaining loop member affixed to the aforesaid end of the handle and extending in spaced relation to 15 and around the exposed portion of the aforesaid bar, said locking pin contained within the handle and having its head normally engaging over the end of the aforesaid bar, a spring mounted in the handle and engaging 20 said pin to normally press it into locking engagement over the end of the bar.

JOHN B. ZORN.
